SPARKPLUG AND PROCESS OF MANUFACTURING THE SAME

Howard J. Beardslee, Jr., Defiance, Ohio, assignor to The Zeller Corporation, Defiance, Ohio, a corporation of Ohio

Filed Apr. 1, 1963, Ser. No. 269,270
5 Claims. (Cl. 29—25.12)

The invention relates to sparkplugs and more particularly to resistor sparkplugs.

In the present state of the art with respect to resistor sparkplugs, the resistor, while within the ceramic insulator, is nevertheless subjected to environmental conditions surrounding the sparkplug. It has therefore been the practice to protect the resistor from the effects of the environment with some electrically inert material. In spite of such protection the surface coating can eventually break down, thus changing the resistor value or allowing the ignition voltage to flash over the outside of the resistor body.

One of the objects of the present invention is to devise a method whereby the resistor can be completely sealed within the sparkplug cavity thereby preventing conditions outside of the sparkplug from effecting any change in the resistor.

Another object is to provide a sparkplug construction having many advantageous features, including not only a completely sealed resistor but also good electrical conductivity between said resistor and the electrical conducting elements at the opposite ends thereof.

With these and other objects in view, the invention consists in the construction as hereinafter set forth.

In the accompanying drawings:

FIGURE 1 is a longitudinal section of a sparkplug insulator showing the relationship of the parts prior to the sealing operation.

FIGURE 2 is a similar view of a complete sparkplug showing the final relationship of the parts after the seal has been accomplished.

As shown in the drawings, the ceramic insulator A, usually made of alumina, has an axial channel therethrough. This channel includes a small diameter portion B extending from the inner end to centrally within the insulator, a larger diameter chamber C extending toward the outer end, and an enlargement D at the extreme outer end. E is the center electrode having a head F seated on the shoulder at the bottom of the central chamber C. G is the resistor within the chamber C and H is the stud having a portion I for fitting the enlargement D and a flange J for seating on the top K of the insulator. The stud H has a depending portion L of reduced diameters, the lower end of which is threaded at M. According to the present invention the sparkplug has permanent seals at both ends of the resistor and as indicated in FIGURE 2, N is the lower seal and O is the upper seal.

One method of manufacturing the sealed sparkplug of FIGURE 2 is illustrated in FIGURE 1. The electrode E is inserted from the top of the insulator to extend through the bore B with the head F seated at the bottom of the central chamber C. The electrode is made of nickel, nickel alloy such as Inconel, or other material which is both electrically conductive and capable of withstanding the combustion temperature and the products of combustion to which the electrode will be subjected in service. Above the head F, there is placed a layer of sealing material N' the volume of which is larger than the final seal N to allow for the shrinkage in size during vitrification. Next, the resistor G is inserted from the top into the chamber C to rest on the layer N'. Above the resistor there is placed a layer O' of sealing material of larger volume than the final seal O to allow for shrinkage. Because of the large

2

initial volume of the sealing material, the upper layer of material O' extends into or adjacent the enlargement D. Therefore the flange J of the stud H is considerably above the top of the insulator before the sealing operation as shown in FIGURE 1.

5 To prevent any possibility of the material in the upper layer O' entering into any minute space surrounding the resistor G, it is necessary that the resistor should completely fill the cavity. Therefore the resistor must be circumferentially coated with an electrically inert material P that will insure that there will be no unfilled space within the chamber C.

10 After the assembly of the parts as thus far described, the structure is subjected to a vitrification and sealing process. The assembly is raised to an elevated temperature which softens the material in layers N' and O' and then pressure is applied to the stud H, compressing the entire assembly, and forcing the stud into the insulator until the flange J rests upon the end K of the insulator.

15 By reason of the temperature and pressure, the layers N' and O' are vitrified and compacted into the shapes illustrated at N and O in FIGURE 2. This forms an effective seal at both ends of the resistor and places the resistor under invariable conditions which are independent 20 of environmental conditions on the outside of the sparkplug.

25 In FIGURE 2 the sparkplug insulator is shown after the seals have been vitrified. It will be noted that the seals N and O are considerably smaller after vitrification 30 than the original layers N' and O'. It will also be observed that the depending portion L of the stud H is embedded in the upper seal O with the threads M extending into the seal. There is no conductive sealing material surrounding the resistor G, due to the fact that the inert 35 coating material P prevented any conductive material in layers O' and N' from flowing around the resistor during the sealing process. This inert material P moved axially with the resistor G when the pressure was applied during the sealing process and assisted in transmitting the pressure 40 to the lower layer of sealing material N' to produce the final gas tight seal N. As shown in FIGURE 2, the resistor G is encapsulated between the two glass seals O and N and therefore the resistor is completely protected from the outside atmosphere by these two seals 45 and the ceramic insulator.

An important feature of the invention is the provision of the electrically inert material surrounding the periphery of the electrical resistor. Without such coating it might be possible for the conductive material in the 50 layers O' and N' to enter into the space surrounding the resistor to a sufficient extent to impair the electrical effectiveness of the resistor. Accordingly an important feature of the invention is to provide suitable electrically inert material in the circumferential coating. The coating must be inert to temperature and electrical conductivity. A suitable material for this purpose is alumina, clay or talc powder or any combination of these materials with a suitable inorganic binder such as sodium silicate. The coating may be applied in various ways. It may be applied 55 to the circumference of the resistor before inserting the resistor into the bore of the ceramic. It may be applied to the walls of the chamber C before placing the resistor into the cavity. The coating material may be applied after the resistor has been placed in the cavity and vibrated or pressed into a solid inert sleeve around the resistor.

60 The resistor coating can be varied somewhat depending upon which of the several methods aforementioned are used in applying it. If the coating is to be applied in the form of powder after the resistor has been inserted 65 into the cavity, then plain talc or alumina or any other 70

equivalent material inert to temperature and electrical conductivity can be used. The powder is vibrated and pressed around the resistor in the cavity to completely fill all small spaces. If the coating is applied before the resistor is inserted into the insulator, then the coating material is preferably carried in some sort of vehicle. It can then be applied by spraying, dipping or by means of a roller or by extrusion. If the coating is to be applied to the resistor as a spray or dip or by means of a roller, then a suitable composition for the purpose is talc and alumina in about equal amounts together with about 5% sodium silicate to act as a binder and enough water to make the mixture of a consistency to be readily workable for whichever method of application is used. Where the coating material is to be applied by extrusion then it is preferable to use a composition containing about 5% clay, 2% sodium silicate and the remainder of talc or alumina or a combination of the two with enough water to provide a consistency suitable for extrusion. It is to be understood that the specific compositions above mentioned can readily be modified by the substitution of materials which are obvious equivalents thereto.

In carrying out the method as hereinbefore described, it is necessary that the layers N' and O' shall be composed of a material which is electrically conductive and is susceptible of being vitrified. Such materials are known in the art and can be either a conductive cement type of seal, or a conductive glass seal. Also the material can be a non-conductive glass seal with a structural conductor extending through the same, such as a wire or spring embedded in the material.

The invention herein described is susceptible of various modifications. For example, the upper and lower seals instead of being composed of electrically conductive material can be made of a non-conductive material and contact with the resistor can be made by means of a wire or by means of a spring. Another modification consists in using for the sealing material a conductive dry cement of the type disclosed in my Patent No. 2,798,980. When using such a material the lower seal is first compacted in place, then the resistor with its surrounding inert coating is placed in the insulator bore and finally the upper seal is compacted into place. Another modification consists in using for the upper and lower seals a self-hardening cement material so that the resistor is contained between upper and lower cement seals and is thereby protected from environmental conditions outside of the sparkplug.

With the invention as above described, I have provided a novel sparkplug construction in which a resistor is secured in the ceramic insulator between two seals. The method of construction is such as to readily permit the resistor to be placed in a cavity within the insulator and then sealed into place.

The novel construction prevents shorting out the resistor either to the cavity or across the terminal ends. It provides a completely encapsulated resistor that cannot come into contact with the outside atmosphere or humidity. The assembly becomes virtually non-destructive when operated within the limits of design.

The improved sparkplug of this invention has the ability of improving the characteristics of the resistor by means of increasing its current rating because heat can easily be dissipated into the surrounding materials. The sparkplug has a longer life due to the increased current rating of the resistor constructed and arranged in the manner set forth herein. By reason of the intimate contact between resistor and ceramic walls, the resistor is enabled to dissipate more heat load into the ceramic body. The encapsulated, hermetically sealed condition produced by reason of this invention improves the resistor voltage characteristics by insulating completely around the resistor and thereby preventing flashover.

What I claim as my invention is:

The method of making a resistor sparkplug com-

75

prising inserting an electrode in one end of an insulator to extend into the longitudinal central hollow portion thereof, applying a layer of conductive vitrifiable material within said insulator in contact with said electrode, inserting a preformed resistor into said central portion to contact with said layer, providing a non-conductive coating in said central hollow portion surrounding said resistor above said layer of conductive vitrifiable material to such an extent that it completely fills the space surrounding said resistor to the level of the top of said resistor, applying a second layer of conductive vitrifiable material within said insulator in contact with said resistor, inserting a plug within said insulator into contact with said second layer and subjecting said plug, said layers of conductive material and said coated resistor to endwise pressure while heating to vitrification temperature to thereby compact said conductive layers, vitrify the same and form permanent seals between the opposite ends of said resistor while preventing access of conductive material into said space surrounding said resistor.

2. The method according to claim 1 wherein after the insertion of said first layer of conductive vitrifiable material and said resistor into said insulator a non-conductive powdered material is tamped into the space around said resistor to completely fill said space to the top of said resistor and thereby prevent subsequent penetration by said vitrifiable material from the first and second layers aforesaid.

3. In a method of making a resistor sparkplug having a resistor within a ceramic insulator and having a pair of conductive vitreous seals at opposite ends of said resistor adjacent an electrode and a conductor respectively, the improvement which consists in first protecting the resistor by impregnating the outer surface with a non-conducting coating to increase the diameter thereof to such an extent that it completely fills the cavity in said ceramic insulator, and then subjecting said seals and coated resistor to endwise pressure while heating to vitrification temperature to thereby compact and vitrify said seals, said coating which completely fills the cavity preventing the entry of any vitrifiable material between the resistor and the ceramic body.

4. The method of making a resistor sparkplug comprising inserting an electrode in one end of an insulator to extend into the longitudinal central hollow portion thereof, applying a layer of conductive vitrifiable material within said insulator in contact with said electrode, inserting a preformed resistor into said central portion to contact with said layer, providing a non-conductive coating in said central hollow portion surrounding said resistor above said layer of conductive vitrifiable material to such an extent that it completely fills the space surrounding said resistor to the level of the top of said resistor, applying a second layer of conductive vitrifiable material within said insulator in contact with said resistor, inserting a plug within said insulator into contact with said second layer and subjecting said plug, said layers of conductive material and said coated resistor to endwise pressure while heating to vitrification temperature to thereby compact said conductive layers, vitrify the same and form permanent seals between the opposite ends of said resistor while preventing access of conductive material into said space surrounding said resistor, said resistor prior to insertion being provided with said non-conductive coating to such an extent that it fits closely into the central hollow portion surrounding said resistor and prevents access into said space of said conductive vitrifiable material during the application of heat and pressure.

5. The method according to claim 4 wherein the preformed resistor prior to insertion into said central hollow portion is coated with a composition comprising alumina and talc bonded with sodium silicate.
